CLAIM

The ornamental design for a medical vest for a mammogram, substantially as shown and described.

DESCRIPTION

FIG. 1 is a front view of a medical vest for a mammogram in accordance with my design.

FIG. 2 is a front view of the medical vest for a mammogram of FIG. 1 with a right flap open.

FIG. 3 is a front view of the medical vest for a mammogram of FIG. 1 with a left flap open.

FIG. 4 is a front view of the medical vest for a mammogram of FIG. 1 with a center seam open.

FIG. 5 is a front view of the medical vest for a mammogram of FIG. 1 with a center seam open.

FIG. 6 is a left side view of the medical vest for a mammogram of FIG. 1, the right side being a mirror image.

FIG. 7 is a left side view of the medical vest for a mammogram of FIG. 1 with the left flap open, the right side being a mirror image.

FIG. 8 is a back view of the medical vest for a mammogram of FIG. 1 with a center seam open; and,

FIG. 9 is a back view of the medical vest for a mammogram of FIG. 1 with a center seam closed.

Any features shown in broken lines in the drawings depict environmental subject matter only and form no part of the claimed design.

1 Claim, 9 Drawing Sheets
